UNITED STATES PATENT OFFICE.

GEORGE H. LAMBERT, OF ASHEVILLE, NORTH CAROLINA.

TEEING-PLATFORM.

1,276,775.

Specification of Letters Patent. Patented Aug. 27, 1918.

Application filed March 19, 1918. Serial No. 223,304.

To all whom it may concern:

Be it known that I, GEORGE H. LAMBERT, a citizen of the United States, residing at Asheville, in the county of Buncombe and

5 State of North Carolina, have invented a certain new and useful Improvement in Teeing-Platforms, of which the following is a full, clear, and exact description.

The object of this invention is to provide 10 a smooth and level or uniform platform for the tee in a golf course, so as to avoid the inconvenience and uncertainty of properly placing the tee directly upon the turf.

The invention consists of a frame adapted 15 to be sunk in the turf and having a tee-supporting surface suspended thereupon, preferably under tension, so that it will be on or about the level of the roots of the grass and thus afford a constant tee of uniform 20 height and a surrounding surface, especially behind the golf ball, that is smooth and even, thereby tending to minimize or avoid liability to sclaffing, as I will proceed now to explain and claim.

25 In the accompanying drawings illustrating the invention, in the several figures of which like parts are similarly designated, Figure 1 is a perspective view showing one form of the platform arranged as in use. Fig. 2 is a top plan view, and Fig. 3 is a cross-section of the platform. Fig. 4 is a longitudinal section of the platform of Figs. 1 to 3. Fig. 5 is a longitudinal section showing a modification of the tensioning means. Fig. 6 is an inverted plan view of 35 part of the platform of both forms.

In both forms of the invention herein shown, the frame comprises longitudinal side members 1 connected by transverse end members 2 and 3 in such way as to produce a rigid structure. 4 is a bar movably mounted upon the frame and between its side members, and upon this bar and the far end member 2 is fixed a strip 5 of rubber-belted or other material that is substantially non-hygroscopic, or water-proof, and smooth, and upon which a rubber, sand or other tee 6 may be supported. In order to keep the strip 5 taut or under tension springs 7 may be interposed between the movable bar 4 and the end bar 3; or such springs may be otherwise applied to the strip; or, as shown in Fig. 5, the movable bar 4 may have applied to it a tension screw

8 extended through the end bar 3 and supplied with an adjusting nut 9 bearing against said end bar 3.

When the movable bar 4 is used, it may be supplied with lateral projections 10 at its bottom which engage slideways 11 on 60 the side-members to hold it in place.

The frame is sunk in the turf so as to rest upon a natural or artificial foundation 12 and with its top surface and strip about on a level with the roots of the grass. The tee 65 is placed upon the strip 5. No matter how rough the surrounding turf may be the golfer is thus insured a smooth, level and uniform playing surface and a constant tee of uniform height. The surface behind the 70 golf ball is smooth and even, and the liability of sclaffing is thereby lessened and a minimum of resistance is afforded when the stroke is low.

The material of the structure should be 75 such as to be substantially unaffected by atmospheric conditions.

Such a teeing platform is durable, and it is especially valuable as a time-saver on a crowded course.

In Fig. 1 the tee 6 is shown as of rubber and fastened to the frame by a flexible connection 13, so as to be always readily available for use.

The platform may be varied in detail and 85 such variations are intended to be included in the claims following.

What I claim is:—

1. A teeing platform, comprising a rigid frame and a tee-supporting strip rigidly 90 fixed to one end of the frame and having tensioning means interposed between its other end and the adjacent end of the frame.

2. A teeing platform, comprising a rigid frame having side members and end members, a tee-supporting strip having one end fixed to one of the end members, a movable bar arranged transversely in the frame and having the other end of the strip secured to it, and a tensioning device interposed between the said bar and the adjacent end member of the frame.

3. A teeing platform, comprising a rigid frame having side members and end members, a tee-supporting strip fixed at one end 105 to one of the end members, a transverse movable bar and guideways for such bar, the other end of the strip being secured to

said bar, and tensioning means connecting said bar and the adjacent end member.

4. A teeing platform, comprising a rigid frame adapted to be sunk in the turf level with its ground surface, a strip of waterproof material suspended by its ends in said frame between the frame's ends and adapted to receive a tee and support it at a substantially uniform height, and spring ten-

sioning means interposed between the frame 10 and the strip.

In testimony whereof I have hereunto set my hand this 18 day of March A. D. 1918.

GEORGE H. LAMBERT.
